UNITED STATES PATENT OFFICE

ALEXANDER INGLETON ROE, OF ORANGE, NEW JERSEY

AUTOMATIC SPEEDOMETER CHART

Application filed June 16, 1931. Serial No. 544,840.

This invention relates to an automatic speedometer chart, the general object of the invention being to provide a strip containing the road map with means for operating or 5 moving the strip from the speedometer, so that the operator of an automobile or other vehicle to which the device is attached, can tell by glancing at the map just where he is, on the road.

10 This invention also consists in certain other features of construction and in the combination and arrangement of the several parts, to be hereinafter fully described, illustrated in the accompanying drawings, and specifically 15 pointed out in the appended claims.

In describing the invention in detail, reference will be had to the accompanying drawings wherein like characters denote like or corresponding parts throughout the several 20 views, and in which:—

Figure 1 is a fragmentary view of an instrument board of a motor vehicle showing the invention applied thereto.

Fig. 2 is a fragmentary view of the chart 25 or map carrying strip.

Fig. 3 is a view looking toward the closed end of the drum.

Fig. 4 is a transverse sectional view through 30 that part of Fig. 1 which carries the invention.

Fig. 5 is a view of the gear wheel.

Fig. 6 is a fragmentary view of part of the dog carrying lever.

Fig. 7 is a section on line 7—7 of Fig. 4.

35 Fig. 8 is a section on line 8—8 of Fig. 4.

Fig. 9 is a view of the dog.

Fig. 10 is a side view of the drum.

In these drawings, the numeral 1 indicates 40 a casing which may be attached to the instrument board A of a motor vehicle or the like, this board having an opening 2 therein with a door 3 closing the opening and having a window 4 therein. A marker 5 is carried by the door and projects into the window as shown in Fig. 1.

A large gear 6 has a stub shaft 7 connected 45 to the center of one face thereof and this shaft extends into a bearing boss 9 formed in one of the side walls of the casing. A friction disk 10 closes the outer end of the boss

and carries a set screw 11 which is threaded into the hub or stub shaft 7, these parts acting to frictionally hold the gears against rotary movement. The gear is provided with the ratchet teeth 12 which are engaged by a 55 dog 13 pivoted to a lever 14 which is pivotally supported intermediate its ends by a bracket 15 in the casing. This lever has its dog carrying end bent at right angles as shown in Fig. 6, so as to properly position 60 the dog to engage the gear.

A spring 16 is connected with the lever and a part of the base and normally holds the dog in lowered position. A leaf spring 17 pushes the dog into engagement with the 65 teeth of the gear. That end of the lever 14 opposite the end which carries the dog is engaged by a cam 18 on a shaft 19 which is geared to a part of the mechanism of the speedometer B and the parts are so arranged 70 that the ratchet wheel 6 will make a step by step movement under the action of the dog and I prefer to space the teeth one-tenth inch so that the ratchet will be moved one-tenth inch for each revolution of the 75 cam which is operated by a gear of the speedometer, which makes one revolution per mile.

A strap 20 has one end fastened to the ratchet wheel 6 as shown at 21 with the major portion of the strap spaced from the 80 wheel and a cylindrical-shaped drum having one end open and has loops 22 on its closed end through which the strap passes so that the drum, as shown at 23, can be detachably connected with the wheel 6 by placing the 85 loops of the drum over the strap as clearly shown in Fig. 4.

The strip carrying the road map is shown 90 at 24 and this strip is placed around the outer circumference of the drum and has its 95 ends passed through a slot 25 in the drum as shown at 26 in Fig. 4, to detachably connect the strip to the drum. The drum is so located with respect to the window 4, that the strip can be seen through the window and the 95 marker 5 cooperates with the road map on the strip to indicate to the operator, just what position on the road he occupies.

The door 3 provides a means for removing 100 the drum so that the strip can be removed

therefrom and a new one placed thereon, after which the drum is again put in place and connected with the wheel 6.

When the teeth on the ratchet wheel are spaced one-tenth of an inch, the map or road strip is marked in one-tenth inches in spaces, each space equaling one mile. Every ten miles may be enumerated and as shown the route is represented on the drum or strip as a straight line. It may be provided with arrows pointing in the direction to be taken, in cross roads or forked roads. The routes may be named or numbered as the case may be. Cities may be marked by a curved line at their boundary lines with notation marks corresponding to a booklet showing streets to be taken until the boundary line is passed where the chart or strip is again set to the proper position by using some line mark when the strip will be ready to guide the operator on the next lap of his journey.

Thus the operator can readily follow the road by simply watching the strip and this device will be of great aid in night driving as there is no necessity to stop to look at signs or inquire for directions, as everything for the proper following of a route is located on the map.

It is thought from the foregoing description that the advantages and novel features of the invention will be readily apparent.

It is to be understood that changes may be made in the construction and in the combination and arrangement of the several parts, provided that such changes fall within the scope of the appended claims.

Having thus described my invention, what I claim as new is:

1. A device of the class described comprising a casing attached to a part of a vehicle, a ratchet wheel rotatably arranged in the casing, a lever pivoted in the casing, a dog carried by the lever and engaging the teeth of the wheel, a cam engaging the lever, means for operating the cam from a vehicle part, a drum carried by the ratchet wheel, a route strip moved by the drum and a window in the casing through which a part of the strip is visible, and a marker projecting into the window, and extending over a part of the strip.

2. In combination with a vehicle having a speedometer and an opening in its instrument board adjacent the speedometer, a door closing the opening, and having a window therein, a marker carried by the door and projecting into the window, a casing attached to the under face of the instrument board enclosing the opening, a ratchet wheel rotatably arranged in the casing, a lever pivoted in the casing, a dog carried by the lever and engaging the teeth of the wheel, a drum detachably connected with the wheel, a route strip carried by the drum and visible thru the window, a cam engaging the lever for

rocking the same, and means for operating the cam from a part of the speedometer.

3. In combination with a motor vehicle including an instrument board and a speedometer, an opening in said board, a door closing the opening, a window in the door, a marker carried by the door and projecting into the window, a casing connected to the under face of the instrument board and enclosing the window, a ratchet wheel rotatably arranged in the casing, friction means for resisting rotary movement of the wheel, a lever pivoted in the casing, a dog carried thereby engaging the teeth of the wheel, a cam engaging the lever for rocking the same, means for operating the cam from a part of the speedometer, a drum detachably connected with the wheel and adapted to be passed through the openings, when the door is opened, and a route strip carried by the drum.

In testimony whereof I affix my signature.

ALEXANDER INGLETON ROE.
